JACOB RUSH SNYDER, OF PITTSBURGH, PENNSYLVANIA, ASSIGNOR TO PERCY E. DONNER, OF PITTSBURGH, PENNSYLVANIA.

QUICK-RECHARGING VALVE.

1,094,945.

Specification of Letters Patent. Patented Apr. 28, 1914.

Application filed August 27, 1912. Serial No. 717,367.

To all whom it may concern:

Be it known that I, JACOB RUSH SNYDER, a resident of Pittsburgh, in the county of Allegheny and State of Pennsylvania, have 5 invented a new and useful Improvement in Quick-Recharging Valves, of which the following is a specification.

This invention relates to railway air brakes, and its purpose is to provide for 10 quickly recharging the auxiliary reservoir in such manner that the triple valve will not fail to go to full release position, and also to enable the partial recharging of the auxiliary reservoirs without releasing the brakes.

15 Generally stated the invention comprises a valve device so arranged as to admit fluid pressure from the train pipe to the auxiliary reservoir until the latter is charged to a point somewhat less than the point of 20 equalization with the train pipe, whereupon such recharging connection is broken and the completion of the recharging of the auxiliary reservoir thereafter takes place through the usual feed groove in the triple 25 valve, thereby insuring the triple valve being moved to full release position.

The accompanying drawing represents a 30 sectional view through the special recharging valve and shows diagrammatically the coöoperating parts of the air brake system.

In the drawings 1 represents the usual 35 train pipe having a connection 2 to the triple valve 3. 4 is the auxiliary reservoir and 5 the brake cylinder. These parts are represented merely diagrammatically, and in miniature.

The recharging valve is connected between 40 the train pipe and the auxiliary reservoir, and comprises a casing formed in three parts or sections, 7, 8 and 9, suitably secured together. In this casing is a control valve 45 and suitable differential piston mechanism for actuating the same. The differential piston mechanism is shown as formed of two diaphragms, to-wit: a large diaphragm 10 clamped between the casing sections 8 and 9, and a small diaphragm 11 clamped between the casing sections 7 and 8. The space 12 between the diaphragms is open to 50 the atmosphere through port 13 so that no pressure can exist between the diaphragms. The large diaphragm 10 is subject to pressure in chamber 30 in the casing section 9, which chamber is connected to the auxiliary 55 reservoir by pipe 14, and the smaller dia-

phragm 11 is subject to pressure in chamber 15 in casing section 7 which is connected to the train pipe 1. The diaphragms 10 and 11 are connected by a stem 16 so that they must move in unison, and which stem preferably is hollow, being provided with the passage 17 connecting with cross port 18 opening into chamber 15, said passage and cross port forming the direct connection between the train pipe and auxiliary reservoir. 60 The lower part of the stem 16 is surrounded by a helical spring 19 interposed between the small diaphragm 11 and a cross web or spider 20 in casing section 15. The lower end of stem 16 carries the regulating valve 70 21, shown in the form of a check valve co-operating with seat 22 in the lower head 23 of the casing section 7, and controlling the train pipe port 24. The valve 21 may be secured to the stem 16 so as to be lifted positively thereby, but preferably has a lost motion connection thereto, such as by the projection 25 on the stem 16 loosely entering the tubular portion 26 of the valve.

The operation of the valve is as follows: 80 We will assume that the triple valve is in application position and the auxiliary reservoir partly or wholly depleted, and it is desired to recharge said reservoir. The admission of pressure fluid to the train pipe 85 lifts valve 21 and the air enters chamber 15 and thence passes by cross port 18 and passage 17 in the stem 16 to chamber 13 and thence through the connection 14 to the auxiliary reservoir. The diaphragms 10 and 11 90 are normally in the position shown in the drawing, and will remain in such position until the pressure in the auxiliary reservoir acting in chamber 30 against the large diaphragm 10 overbalances the pressure in 95 chamber 15, plus the tension of spring 19, acting against the small diaphragm 11. The diaphragms are so proportioned in area and the spring 19 is of such strength that this overbalancing of pressure on the diaphragm 100 10 occurs prior to equalization of auxiliary reservoir pressure with train pipe pressure, and when it occurs it forces the differential piston mechanism downwardly, seating valve 21 and stopping the flow of air from 105 the train pipe to the auxiliary reservoir through this direct connection. The differential piston mechanism and spring can be proportioned to shut off the direct flow of air from the train pipe to the auxiliary reser- 110

voir at any point short of equalization with train pipe pressure. For instance, if the auxiliary reservoir is to be charged to 90 pounds, this valve can be so arranged as to cut off the flow of air therethrough, say at 70 or 80 pounds, as experience may show to be good practice. At this stage the pressure in the auxiliary reservoir is still considerably below maximum train pipe pressure so that as soon as valve 21 closes the full train pipe pressure acts against the outer face of the main piston of the triple valve, and as the inner face of said main piston is subject to the lesser pressure in the auxiliary reservoir, the triple valve is forced to move to full release position, and the completion of the charging of the auxiliary reservoir takes place through the usual feeding groove until the auxiliary reservoir pressure equalizes with the train pipe. While, therefore, providing for the quick recharging of the auxiliary reservoir, this valve is so constructed as to stop such direct charging at some point less than equalization with train pipe pressure, thereby insuring a sufficient preponderance of the train pipe pressure over that directly charged into the auxiliary reservoir as to force the triple valve to full release position. This valve can also be utilized for recharging the auxiliary reservoir when the triple valve is in service application position and without releasing the brakes, by merely admitting the air sufficiently slowly into the train pipe so that it will be taken care of by the passage through the recharging valve and therefore will not force the triple valve to release position. This enables the auxiliary reservoirs to be recharged to the predetermined amount less than full equalization to which the recharging valve is adjusted, and enables the brakes to be held applied while partially replenishing the auxiliary reservoirs, such as is desirable when coming down long grades. If it is desired to fully recharge the auxiliary reservoir when coming down long grades, the triple valves, may, of course, be moved to full release position, but they need not remain long in that position because the auxiliary reservoirs have been already recharged fairly close to their capacity, and consequently, the brakes need remain released for such a short time that the train would not get beyond control.

As the auxiliary reservoir has been practically recharged while the brakes remain applied, the engineer is able to further increase the pressure in the brake cylinders even though he had previously made a full service application, which additional application may be very desirable due to the brake cylinder pressure leaking off, or it may be necessary to secure a higher braking power in the brake cylinders to stop a train of loaded cars than one of empty cars, as the braking

power for freight cars is based upon some predetermined percentage of the light or empty weight and not the loaded weight. Therefore a full service application might not produce the desired result on a train of loaded cars. Consequently it is a convenience to be able to recharge the auxiliary reservoirs without having to release the pressure in the brake cylinders, and then further build up the brake cylinder pressure. 70 75

The recharging valve described obviously can be used with any form of triple valve and in any automatic air brake system, and can be applied to any existing air brake equipment by merely connecting the same 80 between the auxiliary reservoir and the train pipe.

Any form of differential piston mechanism may be used in lieu of the two diaphragms illustrated, and various forms and 85 arrangements of valves and of by-pass connection between the valve and the auxiliary reservoir, will readily suggest themselves to those skilled in the art.

What I claim is:

1. In a fluid pressure brake, the combination with a train pipe, triple valve, auxiliary reservoir and brake cylinder, of a recharging valve device interposed between the train pipe and auxiliary reservoir and including 95 a movable abutment subject on one side to auxiliary reservoir pressure and on its opposite side to train pipe pressure, a valve operatively connected to said abutment and arranged to control communication between 100 the train pipe and the auxiliary reservoir and also controlling communication between the train pipe and the one side of said movable abutment, and a spring acting in conjunction with the pressure on the train pipe 105 side of said movable abutment.

2. In a fluid pressure brake, the combination with a train pipe, triple valve, auxiliary reservoir and brake cylinder, of a recharging valve device interposed between the 110 train pipe and auxiliary reservoir and including differential piston mechanism having its small area subject to train pipe pressure and its large area subject to auxiliary reservoir pressure and arranged to maintain communication from the train pipe to the auxiliary reservoir until the auxiliary reservoir pressure reaches a predetermined point short of equalization with the train pipe and to then close said connection, 115 120 whereby the equalization of the auxiliary reservoir with the train pipe is completed through the triple valve.

3. In a fluid pressure brake, the combination with a train pipe, triple valve, auxiliary 125 reservoir and brake cylinder, of a recharging valve device interposed between the train pipe and auxiliary reservoir and including differential piston mechanism having its small area subject to train pipe pressure 120 125

and its large area subject to auxiliary reservoir pressure and arranged to maintain communication from the train pipe to the auxiliary reservoir until the auxiliary reservoir pressure reaches a predetermined point short of equalization with the train pipe and to then close said connection, whereby the equalization of the auxiliary reservoir with the train pipe is completed through the triple valve, and a spring acting in conjunction with the pressure on the smaller area of said differential piston.

4. In a fluid pressure brake, the combination with a train pipe, triple valve, auxiliary reservoir and brake cylinder, of a recharging valve comprising a casing connected at one end to the auxiliary reservoir and at its opposite end to the train pipe, a connection through said valve from the train pipe connection to the auxiliary reservoir connection, a differential piston in said casing subject on its larger area to auxiliary reservoir pressure and on its smaller area to train pipe pressure, and a valve operatively connected to said differential piston and controlling communication between the train pipe and the auxiliary reservoir and also controlling communication between the train pipe and the smaller area of said differential piston.

5. In a fluid pressure brake, the combination with a train pipe, triple valve, auxiliary reservoir and brake cylinder, of a recharging valve comprising a casing connected at one end to the auxiliary reservoir and at its opposite end to the train pipe, a con-

nexion in said valve from the train pipe connection to the auxiliary reservoir connection, a valve controlling said connection, a differential piston in said casing subjected 40 on its larger area to auxiliary reservoir pressure and on its smaller area to train pipe pressure and operatively connected to said valve, and a spring coöperating with the pressure acting on the smaller area of 45 said differential piston.

6. In a fluid pressure brake, the combination with a train pipe, triple valve, auxiliary reservoir and brake cylinder, of a recharging valve comprising a casing connected at one end to the auxiliary reservoir and at its opposite end to the train pipe, a connection through said valve from the train pipe connection to the auxiliary reservoir connection, a differential piston in 50 said casing subject on its larger area to auxiliary reservoir pressure and on its smaller area to train pipe pressure, a valve operatively connected to said differential piston and controlling communication between the train pipe and the auxiliary reservoir and also controlling communication between the train pipe and the smaller area of 55 said differential piston, and a spring acting in conjunction with the pressure on the 60 smaller area of said differential piston.

In testimony whereof I have hereunto set my hand.

JACOB RUSH SNYDER.
